FOLDING TABLE

Wilbert E. Hardy, Crafton, Pa., assignor to The
McKay Company, Pittsburgh, Pa., a corpora-
tion of Pennsylvania

Application November 7, 1935, Serial No. 48,684

3 Claims. (Cl. 311—80)

My invention relates to folding tables and has for its object the provision of a table structure of such form that the legs thereof can more readily be folded and unfolded than in the case 5 of various structures heretofore employed, is rigid in use, and extremely compact in folded position.

One form which my invention may take is shown in the accompanying drawings wherein Figure 1 is an inverted plan view; Fig. 2 is an 10 elevational view, partially in section; Fig. 3 is an elevational view taken at right angles to the view of Fig. 2; Fig. 4 is a view, on an enlarged scale, taken on the line IV—IV of Fig. 2; Fig. 5 is an enlarged view taken on the line V—V of Fig. 2; Fig. 6 shows the manner in which one 15 pair of legs is disengaged from the table top, and in partially folded position, and Fig. 7 shows the table structure in completely folded position.

The table top 9 may be of circular or other 20 form and of any suitable material. A channel bar is bent to inverted U-form for the purpose of forming legs 10, the mid portion 11 of the bar serving as a cross bar for connecting the upper ends of the legs 10. A brace bar 12 is welded 25 or otherwise secured to the legs 10.

The other pair of legs 13 and 14, are likewise 30 of channel form and are pivotally connected at their upper ends to brackets 15 that are secured to the underside of the table. A brace bar 16 is secured at its ends to the legs 13—14.

At one side of the table, a pair of links 17 are pivotally connected together at their mid 35 portions, and at their upper ends are pivotally connected to the legs 10 and 14, as shown more clearly in Figs. 4 and 5. A pair of links 18 are similarly connected to one of the legs 10 and the legs 13, at the other side of the table.

A rod 20 extends through the lower end of one 40 of the links 17, and one of the links 18, its ends projecting into the channels in the legs 10, while a rod 21 extends through the lower ends of the 45 links 17 and 18, and into the channel legs 13—14.

A pair of recessed blocks 22 are secured to the 45 underside of the table, in position to serve as retaining lugs for the cross bar 11 when the table is set up.

In order to fold or knock down the table, the 50 top 9 is lifted somewhat to raise the blocks 22 clear of the cross bar 11, whereupon the legs 10 can be pushed as a unit toward the legs 13—14, as indicated at Fig. 6. During this movement, the rods 20 and 21 will slide downwardly along the legs, to permit collapsing of the links 17—18. The leg structure can then be swung flatwise 55 against the underside of the table top, to the po-

sition shown in Fig. 7, the brackets 15 being of sufficient dimension to permit the legs 10 to lie behind the legs 13—14.

The brace bars 12 and 16 serve not only to stiffen the legs to which they are connected, but 5 serve also as stop members to positively limit the upward movement of the lower ends of the links 17 and 18, thus further adding to the rigidity of the structure.

I claim as my invention:—

1. A table structure comprising a top, a pair 10 of channel bars bent to inverted U-form and each constituting a pair of table legs, means pivotally connecting the upper portion of one of the bars to the table top, a retaining element on 15 the table top, for holding the upper portion of the other bar against horizontal movement when the table top is resting thereon, a pair of links each pivotally connected at its upper end to a leg of one bar, and at its lower end to the adjacent leg of the other bar, at one side of the table, and a second pair of links at the other side of the table, each pivotally connected at its upper end to a leg of one bar and at its lower end to the adjacent leg of the other bar, the lower 20 pivotal connections in each instance being slideable in the grooves of the legs, and the said pivotal connection to the table top being spaced from said top a distance sufficient to permit the legs to be folded into parallelism with the table 25 top.

2. A table structure comprising a top, a pair of channel bars bent to inverted U-form and each constituting a pair of table legs, means pivotally connecting the upper portion of one of the bars 30 to the table top, a retaining element on the table top, for holding the upper portion of the other bar against horizontal movement when the table top is resting thereon, a pair of links each pivotally connected at its upper end to a leg of one bar, and at its lower end to the adjacent leg 35 of the other bar, at one side of the table, and a second pair of links at the other side of the table, each pivotally connected at its upper end to a leg of one bar and at its lower end to the adjacent leg of the other bar, the pivotal connections at corresponding ends of the links, in one horizontal plane, being slideable in the grooves of the legs, and the said pivotal connection to the table top being spaced from said top a distance 40 sufficient to permit the legs to be folded into parallelism with the table top.

3. A table structure comprising a top, a pair 45 of channel bars bent to inverted U-form and each constituting a pair of table legs, means piv- 50

- totally connecting the upper portion of one of the bars to the table top, a retaining element on the table top, for holding the upper portion of the other bar against horizontal movement when the table top is resting thereon, a pair of links each pivotally connected at its upper end to a leg of one bar, and at its lower end to the adjacent leg of the other bar, at one side of the table, and a second pair of links at the other side of

the table, each pivotally connected at its upper end to a leg of one bar and at its lower end to the adjacent leg of the other bar, the pivotal connections at corresponding ends of the links, in one horizontal plane, consisting of a pair of rods each having its ends slidably supported in the grooves of a pair of legs and extending through the adjacent link ends. 5

WILBERT E. HARDY.
